COMFORTER

Freeman C. Leslie, Chicago, Ill.; Ruby M. Leslie
executrix of said Freeman C. Leslie, deceased

Application December 4, 1943, Serial No. 512,859

3 Claims.

(Cl. 5—334)

1

This invention relates to a new and improved comforter.

The comforter of my invention is of the type in which there are elongated fillers stuffed with down, cotton, wool, or the like, and adapted to be easily removed and replaced from longitudinally extending pockets in the cover, so that the cover may be washed or cleaned without damage to the fillers, the comforter while devoid of zippers, buttons, or other fasteners being constructed, in accordance with my invention, so that the fillers once inserted properly are not visible at the ends and cannot slip out accidentally. The elimination of zippers and other types of fasteners is an obvious advantage aside from materially reducing the overall cost of the comforter.

In the present comforter a separate strip of material is folded lengthwise and laid crosswise of the comforter between the top and bottom cover-pieces near the foot end, so as to be joined to the cover-pieces by the longitudinally extending stitching that defines the parallel pockets in the comforter, thus providing with this one folded strip a plurality of interconnected floating pockets, slings or pouches in the open ends of the elongated filler receiving pockets, which will not interfere with the easy insertion or removal of the fillers, but when spread and applied over the ends of the fillers will positively prevent displacement thereof from the comforter and keep the ends of the fillers far enough removed from the end of the comforter so that they will not be visible in the use of the comforter.

The invention is illustrated in the accompanying drawing, in which—

Fig. 1 is a top plan view of a comforter made in accordance with my invention;

Fig. 2 is a longitudinal sectional detail on a larger scale, taken on the line 2—2 of Fig. 1;

Fig. 3 is a cross-sectional detail on the same scale as Fig. 2, taken on the line 3—3 of Fig. 1, and

Fig. 4 is a view similar to Fig. 2 but on a smaller scale and illustrating the floating pocket strip in an out-of-the-way position in the insertion of the filler.

The same reference numerals are applied to corresponding parts throughout the views.

Referring to Fig. 1, the comforter is designated generally by the reference numeral 5, and comprises a cover 6 made up of top and bottom cover-pieces 7 and 8, which may be of the same or different cloth materials and of the same or different colors, as desired. These cover-pieces are sewed together by longitudinally extending stitches, as indicated at 9, to provide longitudi-

2

nally extending pocket portions 10 to receive the removable elongated fillers 11 that are stuffed with down, wool, kapok, cotton, or the like, as indicated at 12. The pockets 10 are all closed at the head end 13, as indicated by the stitches 14 extending crosswise of that end of the comforter and joining the top and bottom cover-pieces 7 and 8. The pockets are all open at the foot end portion 15, as indicated at 16 in Fig. 2, the top and bottom cover-pieces 7 and 8 being hemmed at that end, as indicated at 17, so that no raw edges are left exposed.

In accordance with my invention, a strip 18 of cloth material, which may be of any type suitable for the purpose of forming the floating pockets, hammocks, slings, or pouches 19 and may or may not be like the materials used in the cover-pieces, is folded lengthwise and laid crosswise of the foot end portion between the top and bottom cover-pieces and joined thereto by the stitching 9. In that way there are no operations added by reason of the provision of this pouch strip and the cost of manufacture is kept to a minimum. Naturally, if the material used for the pouch strip 18 is inexpensive, as it may be, the cost is lowered further. The pouch strip 18 is set in just far enough from the open end 16 of the filler receiving pockets 10 to more or less conceal the pouches 19 from view when the comforter is in use and yet have these pouches reasonably easily accessible, so that one may reach in the open ends of the pockets 10 and spread the pouches and tuck the ends of the fillers 11 therein, in the assembling of the comforter. In the disassembling of the comforter the pouches are, of course, just as easily accessible in the same way for disengagement of the ends of the fillers 11 therefrom, whereupon the fillers are adapted to be pulled out of the pockets 10 past the pouches 19 collapsed as illustrated in Fig. 4. The fillers are, of course, pliable easily to the extent necessary to enter the ends thereof in the pouches 19 or remove the ends therefrom after the fillers have been inserted full length into the pockets 10.

As indicated in Fig. 4, one can easily insert the fillers 11 one at a time into the pockets 10 by thrusting the end of the filler into the pocket by hand as far as the arm will reach, whereupon a cord 20 one end of which is attached to an eyelet 21 on the end of a stick or broom handle, indicated at 22, can be looped around the filler and through the eyelet and extended back along the stick 22 so as to grip the filler fairly securely in a sort of snare to permit its being easily shoved

in all of the rest of the way to a point where the forward end reaches the head end of the cover. Then the cord can be released and the stick withdrawn, taking the cord with it.

The fillers 11 may be of any suitable or preferred construction, it being preferable to have a tube-like covering for the stuffing 12 and a certain amount of stitching through the fillers to hold the stuffing against shifting when the comforter is in use or when the fillers are removed and hung up for airing. The pockets 10 in the cover into which the fillers are entered are of a size just enough larger to admit the fillers easily, and the cover is usually made of rayon or silk, but, of course, any other material suitable for the purpose may be used.

I claim:

1. A comforter, comprising a cover formed by means providing a top cover-piece and bottom cover-piece, a plurality of substantially parallel narrow, elongated pockets formed between the top and bottom cover-pieces by stitching extending lengthwise thereof from end to end, said pockets being closed at one end of the cover and open at the other end, and narrow, elongated fillers removably received in said pockets and extending substantially from end to end thereof, a single continuous filler retaining strip folded lengthwise and disposed between the end portions of said cover-pieces in the open ends of said pockets and having the aforesaid longitudinally extending stitching passing therethrough, whereby to provide in said strip a hammock portion in the open end of each of said parallel pockets between the stitched sides thereof, for support of the end portion of the associated filler that is tucked into the pouch of said hammock portion,

10
15

whereby to prevent endwise displacement of the fillers from the pockets.

2. A comforter as set forth in claim 1, wherein the retaining strip is disposed in inwardly spaced substantially parallel relation to the open ends of said pockets far enough from the ends to render the hammock portions more or less concealed from view but near enough to open the ends for access in the assembling and disassembling of the comforter.

3. A comforter, comprising a series of narrow-elongated filler elements and a cover having a series of parallel narrow, elongated pockets, said series of pockets extending throughout the width of the cover and the individual pockets extending substantially the full length of the cover, the filler elements being of a length substantially equal to the length of the pockets and being removably entered therein endwise, all of the pockets being closed at one end to retain the filler elements, and a single continuous filler retaining strip secured to the cover at the other end and extending crosswise within all of said pockets the full width of the cover, said strip being folded lengthwise and secured to the cover at opposite sides of each of said pockets in the open ends of the pockets to form a plurality of interconnected hammocks, one in each pocket, into which the adjacent end portions of the filler elements are tucked to prevent endwise displacement of said filler elements from the pockets and also substantially conceal the ends of said filler elements from view, said hammocks when slipped off the ends of the fillers and collapsed permitting slippage of the filler elements past the same out of the pockets.
